UNITED STATES PATENT OFFICE

ALEXANDER DOUGLAS MACALLUM, OF NIAGARA FALLS, NEW YORK, ASSIGNOR TO THE ROESSLER & HASSLACHER CHEMICAL COMPANY, OF NEW YORK, N. Y., A CORPORATION OF DELAWARE

ODORANT FOR REFRIGERATION

No Drawing.

Application filed September 4, 1931. Serial No. 561,302.

This invention relates to the use of a warning agent for refrigerants escaping from refrigerating systems and more particularly from systems in which relatively inodorous refrigerants are used. In case of leaks in large refrigerating systems, such as multiple-unit, direct expansion systems in apartment houses, relatively high and dangerous concentrations of refrigerant in the air may result. If the refrigerant is not readily detected by its odor, persons breathing air containing it may not become aware of such leaks before toxic quantities have accumulated.

The object of my invention is to afford means of warning of leakage in refrigerating systems by incorporating in the refrigerant a small proportion of an alkyl ester of bromacetic acid, the vapor of which will escape with the refrigerant and irritate the eyes.

Substances having odorous or irritating properties have heretofore been incorporated in gases to enable leak detection. Practically any stable odorant or irritant with a sufficiently high vapor pressure may be used for such purpose. However, for use in a refrigerant, such a warning agent must possess special properties. It not only must have an appreciable vapor pressure at room temperature, but also must be readily soluble in the refrigerant at the lowest temperature occurring in the refrigerating system, have a freezing point below this temperature, be stable under conditions occurring in the system, have little or no corrosive effect on metals, and must not react with the refrigerant.

I have found that the alkyl esters of bromacetic acid which are lachrymators possess properties which make them especially suited as warning agents in refrigerating systems. I have used from 0.5 part to 4 parts by weight of alkyl bromacetate to 100 parts of liquid refrigerant with good results. This invention is however not limited to these proportions as other proportions may be satisfactory, especially under conditions other than those occurring in my experiments. In general, the best proportions for warning purposes depends upon the nature of the refrigerant and the type of refrigerating machine.

The intensity of the warning effect may be varied by varying the bromacetate content of the refrigerant. Various types of refrigeration systems may require different proportions of the warning agent; for instance the float-chamber type of compression refrigeration system may require more bromacetate than the direct expansion type using a diaphragm expansion valve. I prefer in general to use 1 part by weight of liquid alkyl bromacetate to 100 parts by weight of the liquid refrigerant. The bromacetate may be introduced either before or after charging the system with refrigerant.

Refrigerants with which an alkyl bromacetate may be used as a warning agent comprise those which readily dissolve the substance at the lowest temperature occurring in the refrigerating system, and which do not react with it. An alkyl bromacetate may be used satisfactorily as a warning agent, for example, in a refrigerating system employing methyl chloride as a refrigerant. By means of my invention, persons exposed to concentrations of 0.1% by volume, or even less, of methyl chloride in air are quickly warned of its presence. The invention therefore provides a means for warning persons of concentrations of this refrigerant which are far less than any which would endanger the health, if exposure is limited to any reasonable time. When refrigerant gas containing about 0.5% by weight of an alkyl bromacetate has accumulated in a room, an occupant first feels a stinging sensation in the eyes; when a concentration of 0.1% by volume of refrigerant in the room is reached, the eyes water copiously and within a few minutes it becomes necessary for the person to leave the room. When the eyes are washed out with sodium bicarbonate solution, the unpleasant sensation is relieved.

A particularly good feature of these warning agents is that the irritation not only occurs immediately, but that it becomes greater the longer the exposure, and a tolerance is not established. A further advantage is that warning effects result from leaks from

both the high and low pressure sides of a compression type refrigerating system, showing that the bromacetates do not accumulate in any one part of the system to such a degree as to render their action ineffectual. That these warning agents have no harmful effects when used in the proper proportions, is evidenced by the fact that no injurious effects were suffered by persons engaged in testing their warning properties.

10 Tests made of the action of solutions of ethyl bromacetate in methyl chloride, on samples of iron, brass, and copper showed that under conditions similar to those occurring 15 ring in a refrigerator system, corrosion of the metals was very slight. During a period of 30 days, continuous use of this warning agent in a household refrigerator, there were neither signs of corrosion nor of polymerization. It was also found that the warning 20 effect of the refrigerant containing ethyl bromacetate was substantially unchanged after the 30 day period.

Example 1

25 Methyl chloride containing 1% by weight of tertiary butyl bromacetate was vaporized into a closed room to form a concentration of about 0.1% methyl chloride in the air. After 30 the atmosphere of the room had been stirred by an electric fan for 15 minutes, two observers entered but were forced out of the room in slightly less than one minute by irritation of the eyes.

Example 2

40 The experiment described in Example 1 was repeated, using isopropyl bromacetate in place of the butyl bromacetate. In this case 45 the two observers were forced to leave the room within 5 seconds because of an unusually severe irritation of the eyes.

Example 3

45 A household refrigerator was charged with methyl chloride containing 1% ethyl bromacetate by weight. After continuously 50 operating the refrigerator for two days, a measured sample of the refrigerant was removed from the high pressure side of the pump. This sample was vaporized in a closed test room to give a concentration of 55 about 0.1% methyl chloride in the air. After the atmosphere of the room was stirred by an electric fan for 15 minutes, two observers entered but were forced out of the room in about 90 seconds by irritation of the eyes.

Example 4

60 The experiment described in Example 3 was repeated, except that the refrigerant was removed from the low pressure side of 65 the machine. In this case, the observers were

forced to leave the testing room in less than 60 seconds.

Example 5

The experiment described in Example 3 70 was repeated, except that 1% of methyl bromacetate was used as warning agent in place of ethyl bromacetate and the machine was operated 5 days before making the test. The eye irritation forced two observers from the 75 testing room in 7 and 9 minutes, respectively.

I claim:

1. A composition of matter comprising a relatively inodorous refrigerant containing a lacrymatory alkyl bromacetate in 80 amounts suitable for warning purposes.

2. A composition of matter comprising a relatively inodorous refrigerant containing, in amount suitable for warning purposes, one of the substances selected from the group comprising ethyl bromacetate, methyl bromacetate, tertiary butyl bromacetate and isopropyl bromacetate.

3. A composition of matter comprising a halogenated hydrocarbon refrigerant containing, in amount suitable for warning purposes, one of the substances selected from the group comprising ethyl bromacetate, methyl bromacetate, tertiary butyl bromacetate and isopropyl bromacetate.

4. A composition of matter comprising a halogenated hydrocarbon refrigerant containing 0.5-4.0% of ethyl bromacetate.

5. A composition of matter comprising methyl chloride containing about 1% of ethyl 100 bromacetate.

6. A composition of matter comprising a halogenated hydrocarbon refrigerant containing 0.5-4.0% of isopropyl bromacetate.

7. A composition of matter comprising 105 methyl chloride containing about 1% of isopropyl bromacetate.

Signed at Niagara Falls in the county of Niagara and State of New York this 1st day of September, A. D. 1931.

A. DOUGLAS MACALLUM.
